PENCIL SHARPENER

Filed July 3, 1931

UNITED STATES PATENT OFFICE

HERMAN L. WITTSTEIN, OF NEW HAVEN, CONNECTICUT, ASSIGNOR TO THE ATLAS-
ANSONIA COMPANY, OF NEW HAVEN, CONNECTICUT, A CORPORATION

PENCIL SHARPENER

Application filed July 3, 1931. Serial No. 548,586.

This invention relates to improvement in pencil sharpeners and particularly to pencil sharpeners having removable and replaceable blades, though not so limited.

5 One of the main objects of my present invention is to provide, at a low cost for manufacture, a simple, reliable and convenient sharpener constructed with particular reference to avoiding choking or jamming by 10 broken leads, etc.

A further object of my invention is to provide a superior pencil sharpener which may employ a razor blade as its cutting implement, and constructed with particular reference 15 to securing the maximum service from such blades.

With the above and other objects in view as will appear from the following, my invention consists in a pencil sharpener having 20 certain details of construction and combinations of parts as will be hereinafter described and particularly recited in the claims.

In the accompanying drawing:

Fig. 1 is a view in side elevation of a pencil 25 sharpener constructed in accordance with my invention and showing the removable casing thereof in section;

Fig. 2 is a view thereof in end elevation looking in the direction of the arrow A of 30 Fig. 1 but with the casing removed;

Fig. 3 is a broken detail view in longitudinal section taken on the line 3-3 of Fig. 1 but on a larger scale;

Fig. 4 is a transverse sectional view taken 35 on the line 4-4 of Fig. 1 but shown on the same scale as Fig. 3;

Fig. 5 is a view in elevation of the rotary blade-carrier and pencil-guide detached;

Fig. 6 is an edge view thereof; and 40 Fig. 7 is a broken detail sectional view taken on the line 7-7 of Fig. 5.

The embodiment of my invention herein chosen for illustration consists of a revoluble 45 combined pencil-guide and blade-carrier 10 formed at one end with a cylindrical terminal 11 bearing in an opening 12 in a casing 13 which is removably secured in any approved manner to a supporting-bracket 14 50 having a base-portion 15 by means of which

the sharpener as a unit may be attached to a vertical or horizontal surface.

The end of the combined guide-and-carrier 10 opposite its cylindrical terminal 11 is provided with a shank 16 bearing in a suitable bore in a boss 17 offsetting from the bracket 14 aforesaid. Adjacent the base of the shank 16 the member 10 is provided with an annular series of gear-teeth 18 meshed into by a gear-wheel 19 mounted at the inner 60 end of a drive-shaft 20 rotating in a bore formed in a boss 21 offsetting from the bracket 14 immediately above the boss 17 before referred to. The outer end of the drive-shaft 20 has secured to it a radially-extending 65 arm 22 carrying at its outer end a finger-button 23 in the well-known manner of pencil sharpeners.

The cylindrical terminal 11 is formed axially with a cylindrical chamber or socket 70 24, contracted at its inner end to form a conical terminal 25 therefor and adapted to receive a lead pencil. The wall of the conical socket-terminal 25 is cut away as at 26 to permit the cutting-edge of a blade 27 to project into said chamber for engagement with a pencil therein.

The combined pencil-guide and blade-carrier 10 is also provided with a plate-like offset 28 having its blade-receiving face 29 inclined with respect to the axis of the member as a whole, and so located that the cutting-edge of the blade 27 projecting over the cut-away portion 26 of the wall of the socket-terminal 25 will tangentially engage a pencil. 80

The inner end of the conical portion 25 of the chamber or socket 24 intersects a diametrical passage 30, into one side of which an extension of the wall of the socket 25 extends in the form of a lip 31, providing a 90 quadrant-shaped seat 32 (Figs. 4 and 7) for the support of the pencil-lead and located adjacent the cutting-edge of the blade 27 and facing substantially away from the inner face of the said blade, as clearly shown in Fig. 4 of the drawing and for the purpose as will hereinafter appear.

The plate-like offset 28 of the combined pencil-guide and blade-carrier 10 is further provided with a pair of spaced blade-locating 100

5 lugs 33—33 adapted to extend into the usual aligned central openings 34—34 formed in the blade 27 and between which the said plate is formed with a threaded bore 35 for the reception of the threaded inner end 36 of a knurled clamping-screw 37.

10 The threaded stem 36 of the clamping-screw 37 just above referred to also passes through a central perforation 38 in a clamping-plate 39, preferably formed of sheet-metal and having its respective opposite side-edges 40—40 offset to engage the outer face of the blade 27 adjacent the respective cutting-edges thereof. The said clamping-plate is further provided, on either side of its central perforation 38, with a pair of complementary perforations 41—41 registering with and fitting over the blade-locating lugs 33 before referred to.

20 By forming the clamping-plate 39 with the offset edges 40, its central longitudinal portion is correspondingly raised, and its under face thus made concave. Therefore, when the plate is positioned with its edges 40 bearing against the blade and the screw 37 tightened, the central longitudinal portion of the plate will provide a relatively springy bearing for the cap of the screw and will function as a lock or spring washer to prevent 30 loosening of the screw under the influence of chattering of the blade when in use, thus effectively maintaining the blade in fixed adjustment with relation to the combined pencil-guide and blade-carrier 10.

35 Preferably, the blade-locating lugs 33—33 are sufficiently smaller than the openings 34—34 in the blade 27 to permit a slight movement of the latter with reference to the said lugs, and to provide for accurately gauging 40 the degree to which the cutting-edge of the blade will project into the cut-away portion 26 of the wall of the conical socket 25, I provide, at the point of junction between the plate-like offset 28 and the right-hand end 45 of the body-portion of the combined guide-and-carrier 10, a rib-like abutment 42 which is engaged by the sharp inner edge of the blade for definitely locating the same, as clearly shown in Fig. 1.

50 From the foregoing, it will be seen that when the drive-shaft 20 is rotated by means of the offsetting-arm 22 and finger-button 23, it will effect the rotation of the combined pencil-guide and blade-carrier 10 through the 55 intermediary of the gear 19 and the gear-teeth 18 formed upon the said combined guide-and-carrier, with the result that the blade 27 will be moved therewith and effect the gradual sharpening of the pencil as the same is forced 60 inwardly through the open end of the cylindrical chamber or socket 24 in the terminal 11.

65 The sharpening operation will continue until the end of the lead of the pencil, indicated for the purpose of illustration by the dotted lines 43 in Fig. 5, strikes the wall of

the transverse passage 30, opposite the conical socket-terminal portion 35. In this connection, particular attention is called to the supporting action of the seat 32 in the lip 31 overhanging the said transverse passage when the pencil is reaching the final stages of being sharpened. The thrust imposed upon the sharpened end of the pencil and especially upon the lead thereof by the blade 27, as the same is rotated, is received by the said seat 32 which, however, is so positioned and so faced that in the event that a breakage occurs in the lead, the same may drop away from the blade, through the opposite end of the transverse passage 30, and into the bottom 80 of the casing 13 without jamming.

85 Preferably and as shown, the passage 30 extends diametrically through the combined guide-and-carrier 10 at a point adjacent the contracted end of the socket 25, so that if conditions require, any suitable implement may be passed therethrough to forcibly remove any obstruction, though I wish to have it understood that the said passage will serve its major purpose if it merely provides an opening extending part way through the fixture to the side thereof toward which the seat 32 partially faces.

90 It will be noted that the supporting means, such as the lugs 33—33, are so located with respect to the clearance-cut 26 in the wall of the conical socket 25 that a blade, such as 27, may be reversed end for end to bring a fresh section of its cutting-edge into position for sharpening, and if, as usual, it is a double-edge blade, it may be reversed side for side as well, and thus provide two additional cutting-sections—four in all. During each change of the blade, such as just described, the locating abutment 42 will serve to accurately 100 determine the proper location of the cutting-edge of the blade, regardless of what section thereof is being used, and so minimizes the breakage of the pencil-leads.

105 It will be understood by those skilled in the art that my invention may assume varied physical forms without departing from my inventive concept, and I, therefore, do not limit myself to the specific embodiments herein chosen for illustration, but only as indicated in the appended claims.

110 I claim:

115 1. A pencil sharpener having a rotary blade-carrier provided with an axial pencil-receiving socket and formed with a transverse passage extending therethrough from side to side adjacent the inner end of the said pencil-receiving socket which it intersects to permit the forcible lateral expulsion of broken leads, shavings and dust; a blade positioned 120 to engage and sharpen a pencil as the same is moved axially into the said socket; and a seat extending part way into the said transverse passage in position to support the sharpened 125 130

end of a pencil therein against the thrust of the said blade.

2. A pencil sharpener having a rotary blade-carrier provided with a conical pencil-receiving socket and formed with a clearance-passage opening laterally from the smaller end of the said conical pencil-receiving socket; a blade positioned to engage and sharpen a pencil as the same is moved axially into the said socket; and a lead-supporting seat extending part way into the said lateral clearance-passage in position to support the sharpened end of a pencil therein against the thrust of the said blade.

15 3. A pencil sharpener having a rotary blade-carrier provided with an axial pencil-receiving socket; a double-edged blade carried by the said blade-carrier in position to engage and sharpen a pencil as the same is moved axially into the said socket; a clamping-plate provided with a concave under-face by having its respective opposite edges offset to bear upon the said blade adjacent the respective opposite cutting-edges thereof; and 20 25 screw-means extending through the said clamping-plate and blade for securing the latter to the said blade-carrier, the concave formation of said plate serving to exert a resilient locking effect upon said screw.

30 In testimony whereof, I have signed this specification.

HERMAN L. WITTSTEIN.
